CLAIM

The ornamental design for a four-head electric fryer, as shown and described.

DESCRIPTION

FIG. 1 is a frontal view of a four-head electric fryer, according to my design.

FIG. 2 is a left side view of the four-head electric fryer of FIG. 1.

FIG. 3 is a right side view of the four-head electric fryer of FIG. 1; and,

FIG. 4 is a top view of the four-head electric fryer of FIG. 1.

The surfaces or portions of the article not shown in the drawing or described in the specification form no part of the claimed design.

In the drawings, the broken lines are for illustrative purposes only and form no part of the claimed design.
